[57] CLAIM

The ornamental design for an illuminated holder for combination padlocks, as shown and described.

DESCRIPTION

FIG. 1 is a top, front and left side perspective view of an illuminated holder for combination padlock showing my new design;

FIG. 2 is a left side elevational view thereof;

FIG. 3 is a front elevational view thereof;

FIG. 4 is a right side elevational view thereof;

FIG. 5 is a top plan view thereof; and

FIG. 6 is bottom plan view thereof; and

FIG. 7 is a rear elevational view thereof.

The broken-line showing of the combination padlock in FIGS. 1 and 2 is for illustrative purposes only and forms no part of the claimed design.
